UNITED STATES PATENT OFFICE.

LOUIS WILPUTTE, OF NEW ROCHELLE, NEW YORK, ASSIGNOR OF TWO-THIRDS TO ALICE A. WILPUTTE, OF NEW ROCHELLE, NEW YORK.

COKE-OVEN DOOR.

1,296,892.

Specification of Letters Patent. Patented Mar. 11, 1919.

Application filed April 12, 1918. Serial No. 228,089.

To all whom it may concern:

Be it known that I, Louis Wilputte, a subject of the King of Great Britain, and a resident of New Rochelle, county of Westchester, in the State of New York, have invented certain new and useful Improvements in Coke-Oven Doors, of which the following is a true and exact description, reference being had to the accompanying drawings, 10 which form a part thereof.

My present invention relates to coke oven doors, and particularly to doors for coke ovens of the horizontal coking chamber type, and has for its general object the provision 15 of an improved form of removable closure for the ends of the coking chambers. A more specific object of my invention is to provide a novel coke oven door construction for use in a coke oven having the face of 20 the oven grooved above the ends of the coking chambers so that the door closing the end of a coking chamber may extend into the coking chamber like an ordinary "plug" door, but may be opened by moving it vertically upward from its closing position 25 through the corresponding groove without first moving the door horizontally out of the doorway as is commonly necessary in coke ovens having plug doors as heretofore 30 constructed.

The various features of novelty which characterize my invention are pointed out with particularity in the claims annexed to and forming a part of this specification. 35 For a better understanding of the invention, however, and the advantages possessed by it, reference should be had to the accompanying drawings and descriptive matter in which I have illustrated and described 40 a preferred embodiment of my invention.

Of the drawings:

Figure 1 is a partial side elevation of a coke oven structure.

Fig. 2 is a partial section on the line 45 2-2 of Fig. 1.

Fig. 3 is a plan view of a portion of the coke oven structure shown in Figs. 1 and 2, with the left hand portion of the figure in section on the line 3-3 of Fig. 1, and

50 Fig. 4 is a partial sectional elevation taken similarly to Fig. 2, showing an upper portion of the oven structure.

In the drawings A represents the masonry oven structure, proper, of a typical modern by-product coke oven formed with hori-

zontal coking chambers B, which are separated by heating walls formed with heating flues or combustion chambers C. As shown, the oven structure is formed with vertical grooves A' in the oven side wall, at which 60 one end of each coking chamber B opens. Each groove A' extends from the top of the corresponding coking chamber B to the top surface of the oven structure, proper. Each of these grooves A' forms a guideway or 65 channel in which the door F for the end of the coking chamber B beneath it is vertically movable toward and away from its normal closed position. The door when closed extends from the bottom of the coking 70 chamber to a level somewhat above the top wall of the coking chamber.

In the construction shown, each door F comprises a cast iron frame, or rim, in which is mounted the usual fire brick or refractory door lining F'. The metallic frame of the door is provided with flanges F² which project laterally from the sides of the rim adjacent their outer edges, and overlap the side edges of the doorway when the 75 door is in its closed position. In the construction shown, when the door is in its closed position, the flanges F² bear against the faces of metallic flash plates D which are held between the faces of the battery 80 and the usual buck stays E. There is one of these flash plates D in front of each heating wall. Advantageously, as shown, though this is not essential to the present invention, each flash plate is formed with an external rib D' 85 between the adjacent edge of the doorway and the adjacent buck stays E. The outer side edge of each door flange F², and the adjacent rib D', form the sides of a trough shaped space in which luting clay L is placed to 90 form a tightly sealed joint at each side of the door when the door is closed. The joint at the bottom of the door may be sealed with luting clay L in the usual manner. At the upper end of the door, which, in its 95 closed position, is some distance from the top of the corresponding coking chamber, the metallic rim of the door is extended inwardly beyond the inner edges of the sides of the rim to cover the refractory door lining F', and preferably, as shown, is extended slightly beyond the inner face of the latter. The marginal edge of this portion of the door conforms in shape to the cross 100 section of the groove A, and is separated 105 from the rim by a narrow gap. The door 110

from the side and bottom walls of the latter only by comparatively thin joints, which may readily be luted by clay L . As shown, the metallic top portion of the door is formed with an inclined marginal seat F^3 on which the luting clay L is placed when the door is sealed in its closed position. The ends of the luting surface on the top portion of the rim of the frame F_3 , formed by the seat F^3 , merge into the luting surfaces formed by the lateral faces F^{20} of the flanges F^2 .

At its upper end each door is shown as provided with an eye F^5 for engagement by a suitable hoisting device, (not shown) for raising and lowering the door.

With the door construction forming the present invention, the doors may be opened by simply pulling them vertically upward from their closed positions, and it is one of the advantages of my present invention that the mechanism for raising the doors from their closed position, and lowering them back into that position may be comparatively simple. For example, the mechanism for this purpose may consist of a simple hoisting mechanism mounted on a carriage running along the track and guide rails K , K' and K^2 . With my present invention the advantage of a simple and easy door opening and closing operation is combined with the characteristic advantages of the ordinary plug door heretofore commonly used in coke ovens of the general type illustrated. For example, as with the ordinary plug door, the refractory lining of the door in the closed position of the latter, extends into the coke oven to a depth approximately that of, or actually, as illustrated, a little greater than the thickness of the outer walls of the outer vertical flues C in the heating walls at the opposite side of the coking chamber B . In consequence, the proper amount of heat may be supplied to the extreme end portions of the coal charges in the chambers B , thereby avoiding "black" coke ends. At the same time, the metallic joint forming side flanges F^2 , of the door are removed an appreciable distance from the hot end of the coking charge and from the heating flues C . This tends to prolong the life of the metallic framework of the door, and has the result also of protecting the clay luting, by which the joints at the sides of the door are actually sealed, from excessive temperatures, and thereby reduces the troubles and annoyance from the baking and cracking of the clay luting with resultant gas leakage during the coking operation. It will be understood, of course, that the clay luting seal is broken and destroyed every time an oven door is opened and that the door is newly luted when closed again. The excessive baking of the clay luting may sometimes give trouble also by causing the luting

material to adhere so firmly to the oven door as to make the joint difficult to break in opening the door, and to materially increase the trouble experienced in cleaning off the door and oven preparatory to the fresh luting of the joint when the door is subsequently closed again. By proportioning the parts so that the upper end of the door, when the latter is in its closed position, is appreciably above the top wall of the chamber B , the metallic frame work portion forming the top of the door, and the clay for sealing the joint between the upper end of the door and the bottom and side walls of the groove A' are also protected against direct exposure to the high coking chamber temperatures.

The particular arrangement of flash plates disclosed, with marginal ribs or flanges D' between the adjacent doorways and adjacent buckstays, forms no part of the present invention, but does embody features of novelty invented by me, disclosed and claimed in my co-pending application No. 236,712, filed May 27, 1918, for patent.

In accordance with the provisions of the statutes, I have illustrated and described the best form of my invention now known to me, but it will be apparent to those skilled in the art that changes may be made in the form of the apparatus disclosed without departing from the spirit of my invention, as set forth in the appended claims, and that in some cases, certain features of the invention may be used with advantage without a corresponding use of other features of the invention.

Having now described my invention, what I claim as new and desire to secure by Letters Patent, is:

1. As a new article of manufacture a metallic frame for a coke oven door comprising a rim adapted to support a refractory door lining, and flange portion projecting laterally from the sides of said rim adjacent the outer edges of the latter, and formed with a luting surface running over the top portion of the rim along the side and inner edges of said top portion, and merging at its ends into the lateral faces of said flanges.

2. As a new article of manufacture a metallic frame for a coke oven door comprising a rim adapted to support a refractory door lining, and flange portions projecting laterally from the sides of said rim adjacent the outer edges of the latter, and having the top portion of said rim projecting inwardly beyond the inner edges of the side portions of the rim, and formed with a luting surface running over said top portion along its side and inner edges and merging at its ends into the lateral faces of said flanges.

3. As a new article of manufacture a me-

metallic frame for a coke oven door comprising a rim adapted to support a refractory door lining, and flanges projecting laterally from the sides of said rim adjacent the outer edges of the latter and formed with a luting surface running along the lateral faces of said flanges and over the top portion of the rim along the side and inner edges of said top portion.

10 4. As a new article of manufacture a metallic frame for a coke oven door adapted to close the end of a coking chamber of a horizontal coke oven formed with a door receiving groove in the face of the oven structure extending upward from said cok-

ing chamber, comprising a rim adapted to enter the end of the coking chamber and to surround and support a refractory door lining, and flanges projecting laterally from the sides of said rim and adapted to overlap 20 the portions of the oven structure at the sides of the coking chamber, and having the top portion of said rim projecting inwardly beyond the sides of the rim and adapted to seat against the bottom of said groove, and 25 formed with a luting surface running over said top portion along its side and inner edges.

LOUIS WILPUTTE.
